UNITED STATES PATENT OFFICE.

EDMUND G. STOLTZ, OF GRANITE CITY, ILLINOIS.

CLOSET FLUSH-VALVE.

1,335,763.

Specification of Letters Patent.

Patented Apr. 6, 1920.

Application filed June 3, 1919. Serial No. 301,397.

To all whom it may concern:

Be it known that I, EDMUND G. STOLTZ, a citizen of the United States, residing at Granite City, in the county of Madison and State of Illinois, have invented a new and useful Closet Flush-Valve, of which the following is a specification.

This invention relates to closet flush valves and has for its object to provide a valve 10 that is practically free from the objectionable noise usually present in valves of this class.

A further object is to provide a novel means for positively maintaining a full 15 valve opening during the outflow from the tank.

Another object is to provide a valve closure that may be readily removed for the purpose of inspection and repair.

20 It is also within the province of the disclosure to improve generally and to enhance the utility of devices of that type to which the present invention appertains.

With these and other objects in view as 25 will appear as the description proceeds, the invention resides in the novel arrangement and combination of parts and in the details of construction hereinafter described and more particularly pointed out in the appended claim, it being understood that changes in the precise embodiment of the invention herein disclosed may be made 30 without departing from the spirit or sacrificing any of the advantages of the invention.

The drawing illustrates in side elevation with parts in section a flush valve constructed in accordance with the present invention.

40 Referring specifically to the drawing there is shown at 1 an ordinary flush tank having the outlet pipe 2. Secured to the top of the outlet pipe is a valve seat 3, having formed integrally therewith a collar 4 for 45 the reception of an overflow pipe 5.

The overflow pipe 5 has secured thereto by means of a clamp 6, a supporting bracket 7, the bracket being provided for the attachment of a U-shaped guide member 8, 50 being secured to the bracket by means of set screws 9 or the like. The arms 10 of the member 8 are each provided at the end with a boss 11 in which bearings for a vertically slidable rod 12 are formed. Mounted 55 on the rod 12 between the arms 10 is an oval shaped abutment 13, the same being

preferably screw threaded to the rod as shown. A valve 14 is secured to the end of the rod 12 below the lower arm 10 and is supplied with the usual rubber gasket or 60 washer 15, the same being adapted to seat on the valve 3 to close the same. A coil spring 16 surrounds the rod 12, being interposed between the lower arm 10 and the valve 14 and is under slight compression 65 when the valve is closed.

An arm 17 extends from the boss 11 on the lower arm 10 and has a bifurcated end 18 to which is pivoted a lever 19. The said lever carries at its outer end a float 20. The 70 opposite end 21 of the lever is adapted to engage the abutment 13 to hold the valve in open position, the engaging end of the lever being arcuately shaped. A shoulder 22 on the bifurcated end of the arm 17 serves as a 75 stop to prevent the buoyancy of the float 20 lowering the end 21 of the lever below a point to engage the abutment 13.

The rod 12 is provided at its upper end with a lever 23 for lifting the valve from 80 the valve seat and is the usual structure employed for this purpose.

In operation, with the tank filled, on lifting the rod 12, the abutment 13 will strike the lever 19 and pass by the same, the buoyancy of the float 20 will cause the end 21 to seat under the abutment 13, supporting the valve in open position. As the water in the tank flows out, the float lowers, raising the end 21 of the lever until the abutment is released and the valve closes, the spring 16 exerting sufficient pressure on the valve to seal the same. In the present invention a highly efficient valve is produced, 90 chattering and noisy valve action are prevented by positive engagement of the valve stem by the lever 19, a full valve opening is maintained until the charge of water is released, and not only is leakage of the valve prevented by the additional pressure exerted 100 on the valve by the spring 16 when the valve is closed, but when the valve is open the spring exerting pressure on the valve tends to hold the abutment in engagement with the lever 21 to prevent rattling of the 105 same. The backing plate of the valve 14 may be made of brass or other non-corrosive metal and prevents crimping of the thin feather edge of the rubber gasket 15.

What is claimed is:—

110
In a device of the class described, a flush tank having an outlet, a lever, a bracket

whereon the lever is fulcrumed intermediate its ends, a float on the outer end of the lever, the bracket including a part coöperating with the inner end of the lever to limit the downward movement thereof under the buoyant action of the float, a stem under the control of an operator and slideable in the bracket, a valve carried by the stem and controlling the outlet, a spring carried by the stem and exerting pressure on the valve, and an oval shaped abutment on the stem and engaging the inner end of the lever to hold the valve in open position when the inner end of the stem coöperates with said part of the bracket, the inner end of the

lever being arcuate, whereby when the level of the liquid in the tank has fallen below the float, the abutment will exert a positive lifting action on the inner end of the lever, independently of the weight of the float, 20 thereby releasing the valve for downward movement.

In testimony that I claim the foregoing as my own, I have hereto affixed my signature in the presence of two witnesses.

EDMUND G. STOLTZ.
